DYNAMOELECTRIC MACHINE

Richard W. Dochterman, Fort Wayne, Ind., assignor to
General Electric Company

Filed Jan. 29, 1970, Ser. No. 21,147

Term of patent 14 years

Int. Cl. D13—01

U.S. Cl. D26—5

FIG.1

FIG.3

FIG.2

FIG.4

FIG. 1 is an elevational view of a dynamoelectric machine employing my new design;

FIG. 2 is a side elevational view of the dynamoelectric machine of FIG. 1 as seen from the right in FIG. 1;

FIG. 3 is an end elevational view as seen from the rear in FIG. 1; and

FIG. 4 is an end elevational view as seen from the front in FIG. 1.

The view taken from the left of FIG. 1 is substantially similar to a mirror image of FIG. 2.

I claim:

The ornamental design for a dynamoelectric machine, substantially as shown and described.
